UNITED STATES PATENT OFFICE.

GEORGE CROSSLAND, OF JESSUPS, MARYLAND, ASSIGNOR TO CROMPTON & KNOWLES LOOM WORKS, OF WORCESTER, MASSACHUSETTS, A CORPORATION OF MASSACHUSETTS.

CARPET-WEAVE.

1,367,022.

Specification of Letters Patent.

Patented Feb. 1, 1921.

Application filed January 22, 1920. Serial No. 353,203.

To all whom it may concern:

Be it known that I, GEORGE CROSSLAND, a citizen of the United States, residing at Jessups, in the county of Anne Arundel and 5 State of Maryland, have invented a new and useful Carpet-Weave, of which the following is a specification.

This invention relates to a carpet weave, which may be described as of the Axminster 10 type, as it is well adapted for manufacture on an Axminster loom, with slight modifications.

It is the object of my invention to provide a carpet in which the pile yarn may be 15 inserted in a pre-arranged pattern by the use of yarn spools and tubes of the Axminster type, but in which the pile yarn shall be firmly secured within the fabric, a quality commonly lacking in the regular Axminster 20 carpet.

The finished fabric resembles both Wilton and chenille carpets in certain respects, but is very much simpler to manufacture than either of these types of carpets, and avoids 25 the waste of expensive pile yarn in the back of the carpets which is unavoidable in the Wilton weave.

A preferred form of my invention is shown in the accompanying drawing, which 30 is a longitudinal sectional elevation of my improved weave.

In the production of my improved weave, I use stuffer warps S' and S², binder warps W' and W², pile yarn P, body fillings B', 35 B² and B³, and pile-holding fillings F', F² and F³.

The stuffer warps are preferably disposed in two planes, the warp S' forming the lower plane, and the warp S² forming the 40 upper plane.

Three picks of body fillings B', B², and B³ are preferably inserted between each two consecutive crossings of the binder warps W' and W² and in the drawings they are 45 disposed with the body fillings B' and B² above the stuffer warp S² and the body filling B³ below the stuffer warp S'. The pile yarn is arranged on spools and is fed through sets of tubes, as in the regular Axminster loom, shown for instance in the patents to Horace Wyman, Nos. 490,238 and 50 668,597.

After the binder warps are crossed and the body fillings B' and B² are inserted, the

yarn tubes are depressed to insert the pile 55 yarn P between the upper binder warps, and the pile-holding filling F' is then inserted below the stuffer warp S². The yarn is then raised and the filling F² is inserted 60 above the stuffer warp S². The pile yarn is then again depressed and a third pile-holding filling F³ is inserted below the stuffer warp S², after which the tubes are raised 65 and the pile yarn is cut in the usual manner.

It will be understood that the loom beats up as often as may be found desirable during the operation above outlined. The body filling B³ is then inserted after which the binder warps are again crossed and the operation is repeated. 70

With this construction, the pile yarn tufts are very firmly secured by the three pile-holding fillings F', F², and F³, and are also bound between the two upper body fillings 75 B' and B³. Displacement of the tufts is almost impossible.

It will be understood that the word "pick" as used in the claims indicates either a single or a double thread as may be provided 80 by the particular mechanism on which the weave is produced. I have indicated all of the body and pile-holding fillings as comprising two threads which would be necessary if the fillings were inserted with a 85 needle, as is customary in Axminster looms. It is possible however to insert some of the fillings with a shuttle, in which case a single filling thread of larger size may be used. It may also be desirable to use a 90 heavier or coarser filling for the body fillings B', B² and B³ and it may be desirable to use a lighter stuffer warp S² in the upper plane. The words "pile yarn" are used in the claims to indicate yarn which is used 95 neither as warp nor filling but which is inserted in the fabric by yarn tubes or in any other convenient manner, and which is not mounted in the harness and does not pass through the shed.

I do not wish to be always limited to a specified number of pile-holding picks for each row of tufts, as it may, for instance, be desirable to use five picks to hold a very fine silk tuft in the fabric. 100

All such variations may be made by those skilled in the art, without departing from the spirit and scope of my invention as set 105

forth in the claims, and I do not wish to be otherwise limited to the details herein disclosed, but what I claim is:—

1. A carpet weave of the Axminster type, 5 comprising stuffer and binder warps, pile yarn, and body and pile-holding fillings, three picks of body filling being inserted between consecutive crossings of the binder warps, below and at each outer side of the 10 pile yarn and three picks of pile-holding filling being also inserted between the same crossings to firmly secure the pile yarn within the fabric.

2. A carpet weave of the Axminster type, 15 comprising stuffer and binder warps, pile yarn, and body and pile-holding fillings, said stuffer warps being disposed in upper and lower planes, and each row of pile yarn being secured within the fabric by a plurality of picks of pile-holding fillings, disposed above and below said upper stuffer warp and between consecutive crossings of the binder warps.

3. A carpet weave of the Axminster type, 25 comprising stuffer and binder warps, pile yarn, and body and pile-holding fillings, said stuffer warps being disposed in upper and lower planes, a plurality of picks of body fillings being inserted, some above and some 30 below all of said stuffer warps and between consecutive crossings of the binder warps, and a plurality of picks of pile-holding fillings being inserted between the same crossings of the binder warps to firmly secure the pile yarn in the fabric.

4. A carpet weave of the Axminster type, 35 comprising stuffer and binder warps, pile yarn, and body and pile-holding fillings,

said stuffer warps being disposed in upper and lower planes, and each row of pile yarn 40 being secured within the fabric by a plurality of picks of pile-holding fillings, one above and two below said upper stuffer warp and between consecutive crossings of the binder warps.

5. A carpet weave of the Axminster type, 45 comprising stuffer and binder warps, pile yarn, and body and pile-holding fillings, said stuffer warps being disposed in upper and lower planes, a plurality of picks of 50 body fillings being inserted two above and one below all of said stuffer warps and between consecutive crossings of the binder warps, and a plurality of picks of pile-holding fillings being inserted one above and 55 two below the upper stuffer warp and between the same consecutive crossings of the binder warps, to firmly secure the pile yarn in the fabric.

6. The method of weaving a carpet of Ax- 60 minster type which consists in crossing the binder warps, passing body fillings above and below the stuffer warps, placing pile yarn between the raised binder warps, inserting a plurality of picks of pile-holding 65 fillings above and below a stuffer warp while alternately raising and lowering said pile yarn, thereby binding the same on both sides of said stuffer warp, and finally raising and cutting said pile yarn, inserting an additional pick of body filling, and again crossing the binder warps.

In testimony whereof I have hereunto affixed my signature.

GEORGE CROSSLAND.
